UNITED STATES PATENT OFFICE.

EMIL TALAMINI, OF NEW YORK, N. Y.

DESIGN FOR A TILE-FACING.

42,404.

Specification for Design.

Patented Apr. 9, 1912.

Application filed November 10, 1911. Serial No. 659,659. Term of patent 14 years.

To all whom it may concern:

Be it known that I, EMIL TALAMINI, a citizen of the United States, residing at New York, in the county and State of New York, have invented a new, original, and ornamental Design for a Tile-Facing, of which the following is a specification, reference being had to the accompanying drawing, forming part thereof.

The figure is a plan view of a portion of a tile facing showing my new design the characteristic features of which are the hexagon tiles 2, and the oblong tiles 1, having a side equal to the length of one of the sides of the tiles 2, and having pyramidal ends each side of which is at an angle of sixty degrees to the side of the tile, prolonged, or

which forms an obtuse angle with the side of the tile of one hundred and twenty degrees. Being thus formed, one of the tile 1, may be placed between two of the tile 2, as shown, in regular order and the apexes of the end of the tile 1, 1, 1, will meet at 3, while the sides 4, of the tile 1, and 2, coincide.

I claim:

The ornamental design for a tile facing, as shown and described.

New York, Nov. 7th, 1911.

EMIL TALAMINI.
